UNITED STATES PATENT OFFICE.

FRANK T. MACDONALD, OF SOUTH PENOOSCOI, MAINE.

FLUE OR CHIMNEY CLEANING APPARATUS.

1,315,849.

Specification of Letters Patent. Patented Sept. 9, 1919.

Application filed March 17, 1919. Serial No. 283,057.

To all whom it may concern:

Be it known that I, FRANK T. MACDONALD, a citizen of the United States, residing at South Penobscot, in the county of Hancock 5 and State of Maine, have invented certain new and useful Improvements in Flue or Chimney Cleaning Apparatus, of which the following is a specification.

My invention relates to apparatus for 10 cleaning flues, chimneys or the like.

An important object of the invention is to provide apparatus of the above mentioned character, which is adjustable for operation within flues or chimneys of different sizes.

15 A further object of the invention is to provide apparatus of the above mentioned character, which is adapted to clean square or circular flues or chimneys.

A further object of the invention is to provide 20 apparatus of the above mentioned character which is of simple construction, and is strong and durable.

Other objects and advantages of the invention will be apparent during the course 25 of the following description.

In the accompanying drawings forming a part of this specification and in which like numerals are employed to designate like parts throughout the same:

30 Figure 1 is a side elevation of apparatus embodying my invention;

Fig. 2 is an edge elevation of the same;

Fig. 3 is a horizontal sectional view, taken on the line 3—3 of Fig. 1;

35 Fig. 4 is a vertical sectional view of the apparatus, parts in elevation, showing the attachments for cleaning circular or curved chimneys or flues;

Fig. 5 is an edge elevation of the same; 40 and,

Fig. 6 is a detail section through the attachment.

In the drawings, wherein for the purpose of illustration is shown a preferred embodiment of my invention, the numeral 10 designates a substantially vertical tubular body portion. This tubular body portion has a yoke 11, rigidly secured to its upper end. Pivoted to the yoke 11, as shown at 12, are 45 forked upper arms 13, including sides 14. Pivoted connected with the lower ends of the sides 14, as shown at 15, are lower forked arms 16, including sides 17. The lower ends of the arms 16 have pivotal connection with 50 a vertically movable slide 18, including a tubular portion 19, slidably engaging upon the tubular body portion 10.

Springs 20 have coiled portions carried by the pivots 12, and the outer ends of these springs contact with the upper arms 13, tending to move them outwardly while the inner ends engage the tubular body portion 10, as shown.

The numeral 21 designates an adjustable slide carried by the tubular body portion 10, and having pivotal connection with depending links 22, as shown at 23. The links 22 are pivoted at their lower ends to the slide 18, as shown at 24. A compressible coil spring 25 surrounds the tubular body portion 10 and engages with and beneath the slide 21, the lower end of this spring contacting with an adjustable stop element 26, adapted to be moved longitudinally of the tubular body portion 10 and clamped in adjustment thereto by means of a bolt 27. It is thus seen that the spring 25 serves to raise the slide 21 and links 22, which in turn move the arms 16 outwardly. The spring 25 therefore controls the transverse size or width of the apparatus, which may be varied by changing the tension of the spring 25, causing it to move the slide 21 upwardly for a greater distance.

A flexible element, such as a chain 28, extends through the tubular body portion 10 and is provided at its lower end with a large loop 29, serving as a stop element. This large loop has detachable connection with a swivel 30 by means of a bolt 31, the swivel 30 having connection with a weight 32. The chain 28 extends upwardly through the tubular body portion 10 and has connection with a ring 33, forming an upper stop, connected with a cable 34 or the like. It is obvious that by raising and lowering the cable, the apparatus may be caused to move upwardly or downwardly within the flue or chimney.

In cleaning a flue or chimney, which is rectangular in cross section, and has flat sides, I provide straight blades 35, having cutting edges 36. The blades 35 are provided with lateral extensions 37, attached to the arms 14 and 17 by screws or bolts 38. These extensions 37 have flanges 39, contacting with the sides, and positively preventing turning movement of the blades 35 with relation thereto. The cutting edges 36 of these blades preferably face downwardly in the same direction whereby the scraping action occurs principally upon the downward movement of the apparatus, such downward movement being effected by the weight of the appara-

tus proper, or its combined weight with the ball 32.

When it is desired to clean a flue or chimney having a curved surface, curved blades 40 are arranged upon the opposite sides of the apparatus, and preferably attached to the blades 35 carried by the lower arms 16. These blades are curved longitudinally, as indicated in Fig. 5, and have lower cutting edges 41. The blades 40 carry arms 42, rigidly secured thereto, and these arms are bent to provide sockets 43, having lower undercut portions 44. These sockets are adapted to receive the blades 35, which are held therein by a latch 45, pivoted to the arms 42, as shown at 46. As clearly shown in Fig. 4, the blades 40 extend outwardly beyond the blades 35 for a substantial distance, and when the curved blades are employed, the straight blades do not function as scraping means. All other parts of the apparatus remain the same.

The operation of the apparatus is as follows:

25 When the parts are arranged, as shown in Figs. 1 and 2, the apparatus is lowered into the flue or chimney and the cable 34 is moved upwardly and downwardly causing a reciprocatory movement of the apparatus. 30 The springs hold the blades 35 in proper contact with the side walls of the flue, which scrape therefrom the soot or the like. The upward movement of the apparatus is effected by the pull upon the cable 34, while 35 its downward movement is effected by the weight of the apparatus, or the combined weight of the same with the ball or element 32. As the chain 28 is slightly longer than the tubular body portion 34, it provides a 40 flexible connection between the weight 32 and the tubular body portion 10 and should the apparatus stick on its downward movement, it may be freed by a hammering action of the weight 32.

45 When it is desired to clean a chimney or flue having a curved surface the curved blades 40 are secured to the lower blades 35, as described, and the apparatus used as above indicated.

50 It is to be understood that the forms of my invention herewith shown and described are to be taken as preferred examples of the same, and that various changes in the shape, size, and arrangement of parts may be resorted to without departing from the spirit of my invention or the scope of the subjoined claims.

Having thus described my invention, I claim:

60 1. In apparatus for cleaning a flue or chimney, a body portion, a pair of upper

arms pivotally connected with the body portion, a slide carried by the body portion, a pair of lower arms pivotally connected with the slide and having pivotal connection with the upper arms, blades carried by the arms, an adjustable slide carried by the body portion, connecting means between the adjustable slide and the first named slide, and a coil spring surrounding the body portion and engaging the adjustable slide to move it in one direction. 65

2. In apparatus for cleaning a flue or chimney, a body portion, a pair of upper arms pivotally connected with the body portion, a pair of lower arms having pivotal connection with the upper arms, a slide carried by the body portion to move longitudinally thereof and pivotal connection with the lower arms, an adjustable slide carried by the body portion to move longitudinally thereof, connecting means between the two slides, a coil spring carried by the body portion and contacting with the adjustable slide, and an adjustable stop carried by the body portion to move longitudinally thereof and contacting with the spring to adjust the tension thereof. 75

3. In apparatus for cleaning a flue or chimney, a longitudinal tubular body portion, a slide carried thereby to move longitudinally thereof, arms pivotally connected with the slide and having a flexible connection with the body portion, an adjustable slide carried by the body portion to move longitudinally thereof, connecting means between the two slides, a coil spring surrounding the body portion and engaging the adjustable slide to move it in one direction, a flexible element longer than said body portion arranged within the body portion and capable of longitudinal movement therein, and stops connected to the end of said flexible element. 90

4. In apparatus for cleaning a flue or chimney, a longitudinal tubular body portion, cleaning apparatus carried by the tubular body portion, a flexible element extending through the tubular body portion and capable of longitudinal movement therein, stops connected with the flexible element and arranged above and below the same and spaced for a greater distance than the length of the tubular body portion, and a weight connected with the lower end of the flexible element. 105

In testimony whereof I affix my signature in presence of two witnesses.

FRANK T. MacDONALD.
